UNITED STATES PATENT OFFICE.

ARTHUR J. MASON, JR., OF TAFT, CALIFORNIA.

EARTH SAMPLER.

Application filed June 4, 1925. Serial No. 34,757.

This invention relates to apparatus for securing samples of material forming the walls of a tubular hole manually made in the earth as by drilling for oil, minerals, and 5 the like.

In drilling operations of this character, especially by the rotary method, the true nature of the formations traversed is difficult to ascertain. The material delivered 10 above ground by ordinary drilling operations doesn't show with sufficient accuracy the character of the earth at the point being drilled, and it is therefore necessary to independently secure specially cut samples.

15 This is particularly true where the drilling is through unconsolidated strata.

In rotary drilling, a cumbersome practice of removing the drilling bit and substituting a core barrel, operating like a diamond 20 drill, has grown up. This is a slow and costly process because it entails considerable loss of time and the rotating action of the core barrel in soft formations twists and 25 distorts the core and occasionally burns it beyond recognition. The process of coring with a steel core-barrel at the bottom of a hole has been borrowed from the diamond 30 drill process of metal exploration and is unsuitable for the soft formations which often comprise oil-bearing strata.

In all previous methods, one sample only can be obtained and that must be obtained at the bottom of the well: if it is lost in the hole, the loss is irrecoverable.

35 The object of this invention is to provide a device capable of cutting one or more samples of wall material from the side of a perforation in the earth of any desired, predetermined length, depth or width, and at 40 any predetermined point along the depth of such perforation. The invention consists in mechanism capable of attaining the foregoing and other objects; which can be easily and cheaply made; which is satisfactory in 45 use and is not readily liable to get out of order.

The invention further consists in numerous features and details of construction which will be hereafter more fully set forth 50 in the specification and claims.

Referring to the drawings in which like numerals represent the same parts throughout the several views:

Figure 1 is a side view of the tool of this 55 invention as it appears while descending a perforation in the earth and before the tool

reaches the point where a sample of earth material is to be taken from the side wall of said perforation.

Figure 2 is a sectional view of the tool 60 in the act of procuring the desired sample.

Figure 3 is a perspective view of the tool, taken diagonally from the left and front of Figures 1 and 2.

Figure 4 is a sectional, detail bottom view, 65 taken on the line 4-4 of Figure 2.

Broadly stated, this invention consists in a receptacle, insertable in an earth perforation, equipped with means operable at a particular point in the length of the perforation for cutting earth material from the side wall of the perforation, and conducting 70 said material inside said receptacle, which—with the material therein—may then be removed from the perforation after which 75 the earth material may be taken out of the receptacle and examined.

In Figures 1 and 2 of the drawings, a specific embodiment of this invention is shown operating in a perforation 26 in a 80 body of earth 28, the drawings showing, in the particular case here illustrated, the bottom 30 of the perforation.

The mechanism consists in its simplest form shown in the drawings in a hollow— 85 preferably metallic—tube 32, supported at its upper end on a power actuated rod 34 driven by hammer action toward the end 30 of the perforation 26, in the particular case shown, in a downwardly direction. The 90 lower end portion, specifically approximately the lower quarter of the tube, is bent laterally to one side of the central axis of the tube so that a U-shaped cutting mouth 36 is formed, adapted to be driven into an adjacent side wall of perforation 26 in the earth 95 28 to sever from said side wall a sample earth portion 38 which is by the downward driving action of the tool forced up into the interior of the tube 32. The mouth device 100 36 is prevented from cutting too deeply into the side wall of the earth perforation 26 by a traveling guide 40 on the extreme lower end of the device, traveling ahead of it and engaging the wall of the earth perforation. 105 When the tubular device described is, by the specific mechanism of this invention or otherwise, held against the left hand wall of perforation 26, as shown in Figure 2, while the entire tube 32 is driven downward 110 a length equal to the entire length of the tube, the tube becomes filled with an earth

portion 38 severed from the cut 42 in the earth wall. As all the material below the earth surface where such a device works is more or less moist and it becomes packed by 5 being forced up into the tube 32, it obviously stays there by friction while the operator lifts the tube mechanism by any suitable means as, for instance, the rod 34, out of the perforation 26 to the upper earth surface. If at any time mechanical means are required for retaining the core in the tube, a multiplicity of conventional latches or spring catches 70 (Fig. 2) may be installed in the tube, allowing the material to pass 10 freely up the tube but preventing its downward movement. When the receptacle, viz.: tube 32, reaches this point, the earth sample 38 therein can be removed by any suitable means without departing from this invention.

In the specific case here illustrated, the sampling mechanism of this invention is forced against the wall of the earth perforation 26 by a spring 44 attached to the tube 25 32 on the side opposite to the cutting mouth 36. This spring is sufficiently strong so that under normal conditions, it engages the wall of earth perforation 26, opposite to that engaged by cutting mouth 36, with sufficient 30 force to cause said mouth to cut into the earth as described. The spring 44 is, however, retractile and is so retracted to the position shown in Figure 1 by means of the cord or chain 46 sliding over a post or pulley 35 48 at the lower end of the machine and controlled by a weight 50. In the descent of the tube mechanism of this invention down earth perforation 26, the weight 50 holds spring 44 in retracted position of Figure 1 40 under which condition the entire mechanism slips down the perforation 26 without cutting mouth 34 coming in contact with the wall of the perforation. Premature cutting by the mouth 36 may also be prevented by 45 conventionally wrapping it with soft rope or the like which will be quickly worn away as soon as the tool starts to operate as herein described. When, however, the weight 50 reaches the bottom 30 of the perforation, its 50 control of spring 44 ceases and the spring moves from the position of Figure 1 to that of Figure 2, thus forcing cutting mouth 36 into engagement with the wall of the earth perforation 26 and holding it there during 55 further descent of the tool. The flexible sustaining member 46 should be made long enough so that this release of the spring 44 takes place at a distance sufficiently above the bottom 30 of the perforation so that the 60 tube 32 may be completely loaded with sample earth 38 before the tool itself reaches either weight 50 or the bottom 30 of the perforation. Owing to the fact that flexible member 46 normally travels in a wet, sticky 65 walled hole, collapsing, as shown in Figure

2, is best attained by making it a metal chain in whole or in part. Good results have been attained by making the top foot out of one quarter inch wire and the remainder out of one half inch chain. 70

In actual commercial practical operation, the tube 32 has been made rectangular, as shown, with members 52, 54, 56 and 58 detachably secured in assembled form by removable countersunk bolts 60 and 62 of conventional construction. In the commercial device referred to, the member 52 has been made of material $\frac{3}{4}$ " by 1" and 4' long. The member 54 was $\frac{1}{2}$ " thick, while the side members 56 and 58 have been made of material $\frac{1}{8}$ " thick. In guide 40, all $\frac{1}{4}$ " steel has proved satisfactory in operation. 75

Broadly stated, the mechanism of this invention is not limited as to direction of operation. It can be reversed and pulled upward instead of pushed downward without departing from the invention; neither is it limited to the specific means for releasing the spring 44. 80

The cross sectional shape of the earth carrying tube and the specific location of the cutting mechanism are immaterial to the broad principle of the invention which is, broadly stated, any apparatus which will cut a slice out of the side of a hole in the earth. 90

The mouth 36 and the tube 32 are preferably, but not necessarily, made of substantially continuous and of uniform cross section so that the sample strip 38 cut from the earth wall will slide smoothly into and finally occupy the entire tube 32 without breaking up or mixing up of the material of the sample thus allowing the operator on removing bolts and a plate, as 54, after 105 the device reaches the earth surface, to see the sample in the exact condition in which it was before being cut from the earth wall. 110

One method of driving the sampler downward, heretofore used, has been by inserting conventional jars just above connection 34 and operating them by a wire cable leading to the earth surface, not shown. 115

The spring mechanism can be tripped without the use of the weight touching the bottom of the perforation by the use of tripping mechanism commonly used in ordinary oil well tools, such as easing perforators and tube catches; but the difficulty with such mechanism is that the tube must be dragged out of the hole with the spring extended. The mechanism shown in the drawings is therefore preferred. 120

Having thus described my invention, what I claim as new and desire to secure by Letters Patent is:

1. An earth sampling device movable into and out of a cavity in the earth; said device including cutting means, means carried by the device operable to force said cutting 130

- means into cutting engagement with a side wall of a cavity whereby subsequent movement of the device will cut a sample of earth material from said side wall, and means embodied in the device receiving and retaining said sample for removal from the cavity with said device.
2. An earth sampling device movable into and out of a cavity in the earth; said device including cutting means, and spring means carried by the device operable to force said cutting means into cutting engagement with a side wall of a cavity whereby subsequent movement of the device will cut a sample of earth material from said side wall.
3. An earth sampling device movable into and out of a cavity in the earth; said device including cutting means on one side only, and means operable, when the device reaches a predetermined point in its movement into a cavity, to force said cutting means into cutting engagement with a side wall of the cavity, whereby subsequent movement of the device will cut a sample of earth material from said side wall.
4. An earth sampling device movable into and out of a cavity in the earth; said device including cutting means, and means carried by the device operable, when the device reaches a predetermined point in its movement into a cavity, to force said cutting means into cutting engagement with a side wall of the cavity, whereby subsequent movement of the device will cut a sample of earth material from said side wall.
5. An earth sampling device movable into and out of a cavity in the earth; said device including cutting means on one side only, and means automatically operable, when the device reaches a predetermined point in its movement into a cavity, to force said cutting means into cutting engagement with a side wall of the cavity, whereby subsequent movement of the device will cut a sample of earth material from said side wall.
6. An earth sampling device movable into and out of a cavity in the earth; said device including cutting means, and automatic means carried by the device operable, when the said device reaches a predetermined point in its movement into a cavity, to force said cutting means into cutting engagement with a side wall of the cavity, whereby subsequent movement of the device will cut a sample of earth material from said side wall.
7. An earth sampling device movable into and out of a cavity in the earth; said device including a cutting element, normally restrained means operable upon release, when the device is within a cavity, to force said cutting element into cutting engagement with a side wall of the cavity whereby subsequent movement of the device will cut a sample of earth from said side wall, and means for releasing said normally restrained means.
8. An earth sampling device movable into and out of a cavity in the earth; said device including a cutting element, normally restrained means carried by the device operable upon release, when the device is within a cavity, to force said cutting element into cutting engagement with a side wall of the cavity whereby subsequent movement of the device will cut a sample of earth from said side wall, and means for releasing said normally restrained means.
9. An earth sampling device movable into and out of a cavity in the earth; said device including a cutting element, normally restrained means operable upon release, when the device is within a cavity to force said cutting element into cutting engagement with a side wall of the cavity whereby subsequent movement of the device will cut a sample of earth from said side wall, and automatic means for releasing said normally restrained means.
10. An earth sampling device movable into and out of a cavity in the earth; said device including a cutting element, normally restrained means operable upon release, when the device is within a cavity, to force said cutting element into cutting engagement with a side wall of the cavity whereby subsequent movement of the device will cut a sample of earth from said side wall, and means carried by the device for releasing said normally restrained means.
11. An earth sampling device movable into and out of a cavity in the earth; said device including a cutting element, normally restrained means operable upon release, when the device is within a cavity, to force said cutting element into cutting engagement with a side wall of the cavity whereby subsequent movement of the device will cut a sample of earth from said side wall, and automatic means carried by the device for releasing said normally restrained means.
12. An earth sampling device movable into and out of a cavity in the earth; said device including a cutting element, normally restrained means for forcing said cutting element into cutting engagement with a side wall of a cavity in which the device is disposed, and means operable upon predetermined movement of the device into a cavity to release said normally restrained means and upon predetermined movement of the device out of the cavity to restore said last named means to normal condition.
13. An earth sampling device movable into and out of a cavity in the earth; said device including a cutting element, normally restrained means carried by the device for forcing said cutting element into cutting engagement with a side wall of a cavity in which the device is disposed, and means op-

- erable upon predetermined movement of the device into a cavity to release said normally restrained means and upon a predetermined movement of the device out of the cavity to restore said last named means to normal condition.
14. An earth sampling device movable into and out of a cavity in the earth; said device including a cutting element, normally restrained means carried by the device for forcing said cutting element into cutting engagement with a side wall of a cavity in which the device is disposed, and means carried by the device operable upon predetermined movement of the device into a cavity to release said normally restrained means and upon predetermined movement of the device out of the cavity to restore said last named means to normal condition.
15. An earth sampler movable into and out of a cavity in the earth; said sampler including a cutting element, a device for forcing said cutting element into cutting engagement with a side wall of a cavity in which the sampler is disposed, and means normally restraining said device against operation, said means being operable by engagement with a fixed element within the cavity to release said device for operation.
16. An earth sampler movable into and out of a cavity in the earth; said sampler including a cutting element, a device for forcing said cutting element into cutting engagement with a side wall of a cavity in which the sampler is disposed, and means normally restraining said device against operation, said means being operable by engagement with the base of the cavity to release said device for operation.
17. An earth sampler movable into and out of a cavity in the earth; said sampler including a cutting element, a device for forcing said cutting element into cutting engagement with a side wall of a cavity in which the sampler is disposed, and weight means normally restraining said device against operation, said means being operable by engagement with a fixed element within the cavity to release said device for operation.
18. An earth sampler movable into and out of a cavity in the earth; said sampler including a cutting element, a device for forcing said cutting element into cutting engagement with a side wall of a cavity in which the sampler is disposed, and weight means normally restraining said device against operation, said means being operable by engagement with the base of the cavity to release said device for operation.
19. In mechanism of the class described, an earth retaining receptacle normally slideable in an earth perforation without contacting its side walls, an intake mouth for the receptacle, provided with a cutting edge, capable of movement into engagement with a side wall of the earth perforation, means causing such engagement of the mouth with the adjacent wall, means forcing the receptacle along the earth perforation wall to cause earth cut from the wall to pass into the receptacle, and a guide shoe (40) ahead of the receptacle preventing the cutting edge of the mouth entering the earth wall beyond a predetermined depth.
20. In mechanism of the class described, an earth retaining receptacle normally slideable in an earth perforation without contacting its side walls, an intake mouth for the receptacle, provided with a cutting edge, capable of movement into engagement with a side wall of the earth perforation, means set in operation by engagement with a fixed object in the earth perforation, causing such engagement of the mouth with the adjacent wall, means forcing the receptacle along the earth perforation wall to cause earth cut from the wall to pass into the receptacle, and a guide shoe (40) ahead of the receptacle preventing the cutting edge of the mouth entering the earth wall beyond a predetermined depth.
21. In mechanism of the class described, an earth retaining receptacle normally slideable in an earth perforation without contacting its side walls, an intake mouth for the receptacle, provided with a cutting edge, capable of movement into engagement with a side wall of the earth perforation, means set in operation by engagement with the bottom of the earth perforation, causing such engagement of the mouth with the adjacent wall, means forcing the receptacle along the earth perforation wall to cause earth cut from the wall to pass into the receptacle, and a guide shoe (40) ahead of the receptacle preventing the cutting edge of the mouth entering the earth wall beyond a predetermined depth.
22. In mechanism of the class described, a sampler for traversing an earth perforation and having a cutting mouth, and a normally restrained spring carried by the sampler releasable under predetermined conditions for movement into engagement with the side wall of the perforation at one point to thereby force said cutting mouth into engagement with said side wall at another point.
23. In mechanism of the class described, a sampler for traversing an earth perforation having a cutting mouth engageable with a side wall of the perforation, a spring carried by the sampler engageable with an opposite wall of the earth perforation, and means releasable at a predetermined point normally retracting said spring.
24. In mechanism of the class described, a sampler for traversing an earth perforation having a cutting mouth engageable with a side wall of the perforation, a spring capable of movement into engagement with a

carried by the sampler engageable with an opposite wall of the earth perforation, and a flexibly suspended weight normally retracting said spring.

25. In mechanism of the class described, a sampler for traversing an earth perforation having an open bottom laterally pointed mouth engageable with a side wall of the perforation, a flat spring (44) attached to the sampler at some distance from said mouth, normally engageable with an opposite wall of the earth perforation, a pulley

(48) on the sampler between the lower ends of the mouth and spring, a flexible suspending member 46 attached to the spring, passing over the pulley and a weight (50) on the end of the flexible member sufficiently large to, when sustained by the flexible member, retract the spring, for the purposes set forth.

15. In witness whereof, I have hereunto subscribed my name.

ARTHUR J. MASON, JR.
